UNITED STATES PATENT OFFICE.

THOMAS LITWILLER AND JOHN LEADER, OF MORTON, ILLINOIS, ASSIGNEES TO GETZ
POWER WASHER CO., OF MORTON, ILLINOIS, A CORPORATION OF ILLINOIS.

WASHING MACHINE.

Application filed February 3, 1921, Serial No. 442,336. Renewed December 7, 1922.

To all whom it may concern:

Be it known that we, THOMAS LITWILLER and JOHN LEADER, citizens of the United States, residents of Morton, in the county of 5 Tazewell and State of Illinois, have invented new and useful Improvements in Washing Machines, of which the following is a specification.

This invention has reference to washing 10 machines, and particularly to that type including a clothes container or tub which is mounted for movement in the frame of the machine.

The invention has for its principal object 15 to provide a controllable means for the tub moving means; such controllable means movable to different positions and adapted in one of its positions to impart movement to the tub and in another of its positions 20 adapted to restore the tub to normal stopped position, without stopping the movement of the tub moving means.

A further object of the invention is to 25 provide means for oscillating the tub and controlling such oscillation, which said means are void of the usual and customary spring constraining means for returning the tub to its normal position after each movement and for balancing the tub, and employing in place thereof a simple form of 30 link connection with the tub coupled to a pitman operated from a crank connected to the transmission gearing of the machine. Such link being shiftable thru the agency 35 of a lever for placing the link alternately in operating and non-operating positions. The non-operating position of said link being locked by reason of the relation of the lever thereto, but without affecting the actuation of the pitman, whereby, the pitman 40 may idle during the operation of the transmission mechanism.

The invention has for a further object to 45 provide a controllable means for the tub oscillating means which is adapted to give to the tub a variable movement, such movement being under the full control of an attendant and being dependent on the position to which the controllable means is adjusted. In one position of the controllable 50 means movement may be imparted to the tub, in another position of the controllable means the tub is restored to its normal stopped position, a variable movement being imparted to the tub as the controllable 55

means is moved or held between such two described positions.

The invention comprises essentially an oscillatory tub or container; a transmission mechanism; a link having a slidable relation with a pivot member secured to the tub to one side of its pivotal axis; a pitman pivotally connected to one end of the link and also having a pivotal connection with a crank included in the transmission, and a lever having a pivotal connection with the link at the end opposite to the end to which is connected the pitman. The pivotal axis of the tub and the pivot member are preferably contained within an arc struck from 60 the fulcrum point of the lever when the tub is in its normal position. This makes it possible when the pivotal connecting point of the lever with the link is in coincidence with the pivotal axis of the tub, and the pivot member on the tub is located at the 65 outer end of the link, to oscillate the tub on its pivotal axis. It further provides that, when the lever is shifted to bring the pivotal connecting point of the lever with the 70 link into axial coincidence with the pivot member on the tub, that the link may idle on said pivot member during its oscillation by the pitman without imparting oscillation to the tub, the tub being locked against oscillation and held in a normal position by the lever having been moved to a position 75 between the pivotal axis of the tub and the pivot member thereon.

A structure such as we have described 80 embodies the very fewest number of parts, and omitting as it does the constraining and balancing springs heretofore considered necessary in devices of this character, not only materially simplifies the structure, but reduces the first cost and relieves the machine 85 of the jar incident to the sudden expansion and contraction of the springs.

That the invention may be more fully understood, reference is had to the accompanying drawings, forming a part of the present description and disclosing a preferred embodiment of the invention in which:—

Fig. 1 is a side elevation of a washing machine embodying our improved tub oscillating and controlling means, dotted lines indicating the movement of the parts;

Fig. 2 is a vertical cross-section, as the same would appear, if taken on the line 2—2 of Fig. 1;

Fig. 3 is a detail view of the tub, link, pitman, crank and lever operating and controlling means, shown in tub oscillating position in full lines, and in dotted lines, illustrating the oscillatory positions thereof;

Fig. 4 is a view somewhat similar to Fig. 3, except that the lever has been moved to shift the link into inoperative position, the dotted lines denoting how the link will idle on the pivot member on the tub as the pitman bar is reciprocated;

Fig. 5 is a perspective view of the link, and

Fig. 6 is a detail in plan as the same would appear if taken on the line 6—6 Fig. 1.

Like characters of reference denote corresponding parts throughout the figures.

The machine includes a frame made up of the four corner posts or legs 1 connected at the top by a head frame 2 and at the bottom by a base frame 3. While no inclosing casing for the machine is shown, it is to be understood that such a casing may be provided, whereby the machine may be sold as a cabinet machine.

4 designates a tub or clothes container of a type not uncommon in the art, mounted preferably for oscillatory movement in the machine frame. To its sides are secured plates 5 connected by a rod 6, and each plate has a trunnion 7 in axial alignment with the trunnion on the other plate, and said trunnions are journaled in frame parts 8 and 9, respectively. These trunnions form the pivotal axis for the tub. Ordinarily in machines embodying an oscillatory tub of the character shown, restraining and balancing springs are used, but these are omitted as being unnecessary in our machine.

Essentially, the tub oscillating and controlling means comprise a link 10, a pitman bar 11, a crank 12 and a lever 13, although of course, there is included a transmission mechanism for imparting movement to the crank 12 from the source of power, in this instance an electric motor 14. The motor and transmission mechanism are preferably supported on the machine base. The motor 14 has a small belt wheel 15 driving a belt 16 engaging a larger belt wheel 17 carried on a shaft 18 to which is also attached a pinion 19 meshing with a gear wheel 20 on a shaft 21 to which is connected the crank 12 and also a bevel gear wheel 22 in mesh with a bevel gear wheel 23 on the lower end of an upright wringer shaft 24.

The pitman bar 11 and the crank 12 are of the usual construction. The link 10 is an elongated bar having a longitudinal, preferably, rectangularly shaped slot 25. At one end, the link is formed with a turned back lip, plate or ear 26, spaced from the main body of the link so as to provide a short channel 27, see Fig. 5, and said lip, plate, or ear has a laterally extended short pivot

member 28. The opposite end of the link is formed, preferably, with a depending ear or plate 29 which has a laterally extended short pivot member 30. Slidable in the slot 25 of the link 10, when the latter is reciprocated by the lever 13, as we shall explain, is a sectional bearing block 31, see Figs. 1 and 2, which is clamped about a pivot member 32 connected preferably to a side of the tub and preferably in horizontal spaced relation, a suitable distance from the trunnion 7 on the corresponding side of the tub, see Figs. 3 and 4. The axes of the trunnion 7 just referred to and the pivot member 32 on the tub would be intersected by an arc of a circle struck from a pivot member 33 on a frame part 34, when the tub is in its normal position, and the pivot member 33 serves as the fulcrum on which the lever 13 is oscillated. When the parts are assembled and in operative positions the lever 13 extends up and alongside the tub and frame in the position shown in Fig. 1, the main body of the lever being to one side and to the left of the trunnion 7 and its upper end seated in a depression 35 in a member of the head frame of the machine, see Fig. 6. This tends to hold the parts against accidental displacement, due to vibration, there being enough resiliency in the lever bar, due to its upright position to cause it to seat itself in said depression when swung to such position. When the parts are assembled a lateral extension 36 of the lever 13 has a pivotal connection with the pivot member 28 on the link 10, and the pitman bar 11 has a pivotal connection at its lower end with the crank 12, and a pivotal connection at its upper end with the pivot member 30 on the link 10, all of which is shown.

In the operative position of the tub, with the lever thrown back, the pivotal connection of the lever with the pivot member 28 on the link 10 is coincident with the axis of the trunnions 7 on the tub. Therefore, when the pitman bar 11 is reciprocated, the pressure is approximately in line with the pivot member 32 on the tub and the latter may be oscillated on its pivotal axis, the link idling on the pivot member 28 having a pivotal connection with the extension of the lever, best seen in Fig. 3.

To place the tub operating parts in an inoperative position, to prevent oscillation of the tub and retain it in such position, the attendant, without turning off the source of power, will grasp the lever 13 and move it forwardly from the full line position in Figs. 1 and 3 to the dotted line position in Fig. 1 and full line position in Fig. 4. This movement will slide the link 10 on the bearing block 31, the latter seating itself in the channel 27 between the main body of the link and the lip, plate or ear, 26 thereof, and in such position the axis of the pivot mem-

ber 32 in the block and the pivot member 28 on the link will be coincident. Also, the main body of the lever has been moved across the axis of the trunnion 7 and positioned between the trunnion and the pivot member 32 on the tub locking the parts against oscillation, except, that as the pitman bar 11 is reciprocated, it may impart oscillation to the link 10 and it will idle on its pivotal connection with the lever thru the pivot member 28 all of which it is believed will be understood.

The arrangement of the parts is simple, yet effective, and noiseless, and no danger of stripping gearing, cramping clutch parts and eliminating entirely the danger of being hurt by being caught in movable parts in operative connection with the tub.

We have illustrated the tub 4 in merest outline and the pivot member 32 connected to the side thereof. It is to be understood, however, that in machines of this character and particularly of the oscillating type, it is not uncommon to provide a saddle for the tub, i. e. a frame to brace it and in that event the pivot member 32 would be connected thereto, and the trunnions 7 would also be connected thereto, obviating the use of the plates 5 and cross bar 6.

It should also be borne in mind that the link and lever construction shown makes it possible, as the lever is moved from the position shown in Fig. 4 to Fig. 3 that the tub oscillation is slow with a short stroke gradually increasing until the full stroke is reached. The reverse of this is also true when the lever is moved from the position shown in Fig. 3 to Fig. 4. Then the oscillation is gradually slowed down until it stops. Also, the lever may be moved to different positions between the limits of its strokes, thereby lessening or increasing the movement of the tub, depending on the position of the lever. This variable speed is useful particularly when washing fine fabrics, where a slow speed of oscillation is desirable.

As will be apparent from the foregoing, the link 10 is primarily the controllable means, and in this instance is selected as the means included in the operative connections, between the operating means and the tub, to impart movement to the tub and to stop and restore the tub in normal position, being adapted to be adjusted through the operation of the manually movable lever 13.

By "normal" position of the tub, it is to be understood that that is the position the tub occupies when it is stopped so that the lid or cover thereof may be removed by an attendant to permit the removal of clothes or fabrics from the tub and the placing of other articles or materials therein. Also, by the use of the word "restore" we mean the bringing back or righting of the tub to

"normal" position at the same time that the operating means is made ineffective so far as operating the tub is concerned, yet without disturbing the movement of the operating means.

We have elected to show a very simple yet effective controllable means, realizing, however, that it is possible to vary the structure by the adaptation of other movements, all within the range of skilled mechanics familiar with the art in question, and we therefore do not wish to be confined to the precise construction shown.

What we claim is:

1. In a machine of the character described, in combination, a tub mounted for movement and means to move said tub, including an adjustable means adapted when adjusted to one position to restore said tub to its normal position and stop its movement.

2. In a machine of the character described, in combination, a tub mounted for movement and means to move said tub, including an adjustable means adapted when adjusted to one position to restore said tub to its normal position and stop its movement, without stopping the movement of said moving means.

3. In a machine of the character described, in combination, a tub mounted for movement and means to move said tub, including a controllable means movable to different positions and adapted in one of its positions to impart movement to the tub and in another of its positions adapted to restore the tub to normal stopped position.

4. In a machine of the character described, in combination, a tub mounted for movement, means to move said tub, including a controllable means movable to different positions and adapted in one of its positions to impart movement to the tub and in another of its positions adapted to restore the tub to normal stopped position without stopping the movement of said moving means.

5. In a machine of the character described, in combination, a tub mounted for movement, an operating means, operating connections between said tub and said operating means, and a controllable means in said operating connections having selective positions, in one of which the operating connections to the tub are effective for tub movement and in another of which such operating connections are ineffective for tub movement and the tub is restored and held in normal stopped position, and manually operable means for moving said controllable means.

6. In a machine of the character described, in combination, a tub mounted for movement, an operating means, operating connections between said tub and said operating means, including a controllable means movable to predetermined positions and in selective positions therebetween to impart a

- variable movement to said tub, and in one of such predetermined positions to restore the tub to normal stopped position.
7. In a machine of the character described, in combination, a tub mounted for movement and lever means for operating said tub having a variable fulcrum position, said means including a controllable means for varying the fulcrum point of said operating means to move the tub or to restore it to normal stopped position.
8. In a machine of the character described, in combination, a tub mounted for movement, means for operating said tub; a controllable means for said operating means including lever means, connections between said operating means and said controllable means, said controllable means being adapted to vary the fulcrum relation between said controllable means and said tub to permit the operating means to move the tub, or to restore the tub to normal stopped position.
9. In a machine of the character described, in combination, a tub mounted for oscillatory movement, a member projecting from said tub, a link slidable on said member, a lever having a pivotal connection with one end of said link, for reciprocating the latter alternately to operative and inoperative positions and during the return to the latter position automatically bringing the tub to its normal position, an operating mechanism, and operating connections between said link and said mechanism.
10. In a machine of the character described, in combination, a tub mounted for oscillatory movement, a member projecting from said tub, a link slidable on said member, a lever having a pivotal connection with one end of said link, for reciprocating the latter alternately to operative and inoperative positions and during the return to the latter position automatically bringing the tub to its normal position, a pitman bar pivotally connected to the opposite end of said link, a crank connected to said pitman, and means to operate said crank.
11. In a machine of the character described, in combination, a tub mounted for oscillatory movement, a pivot member on the tub in spaced relation to the pivotal axis of the tub, a link slidable on said member, a lever fulcrumed at its lower end to the machine frame, the pivotal axis of the tub and the pivot member located in an arc struck from the fulcrum point of said lever the tub being in its normal position, means pivotally connecting one end of said link with said lever, an operating mechanism and operating connections between said link and said mechanism.
12. In a machine of the character described, in combination, a tub mounted for oscillatory movement, a pivot member on the tub in spaced relation to the pivotal axis of the tub, a link slidable on said member, of the tub, a link slidable on said member, a lever fulcrumed at its lower end to the machine frame, the pivotal axis of the tub and the pivot member located in an arc struck from the fulcrum point of said lever the tub being in its normal position, means pivotally connecting one end of said link with said lever, a pitman bar pivotally connected to the opposite end of said link, a crank connected to said pitman, and means to operate said crank.
13. In a machine of the character described, in combination, a tub mounted for oscillatory movement, a pivot member on the tub, a slotted link to receive said member, said link being slidable from operative to inoperative position, means to reciprocate said link, a lever in pivotal connection with said link, said last mentioned pivot being coincident with the pivotal axis of the tub when the parts are in normal operative position, and coincident with the axis of the pivot member when the parts are in inoperative position.
14. In a machine of the character described, in combination, a tub mounted for oscillatory movement, a pivot member on the tub in spaced relation to its pivotal axis, a block on said member, a link slotted to receive said block and slidable thereon, said link at one end formed with a turned back lip spaced from the body of the link so as not to interfere with said block, and at its opposite end formed with a depending ear, a pitman bar pivotally connected with said ear, a crank connected with said pitman, means to operate said crank, a lever, means pivotally connecting the body of said lever with the lip on said link, and locking means in the frame for the lever.
15. In a machine of the character described, in combination, a frame, a tub mounted for oscillation in said frame, and operating means for the tub comprising a pivot member arranged in spaced relation to the axial center of the tub, a pivotal controlling means in said operating means, and manually operable means for moving the axis of said controlling means alternately into coincidence with the axis of the tub and the axis of said pivot member, without stopping the movement of said operating means.
16. In a machine of the character described, in combination, a frame, a tub mounted for oscillation in said frame, and operating means for the tub comprising a pivot member arranged in spaced relation to the axial center of the tub, a controlling means in said operating means, said controlling means including a pivot member arranged to be brought into axial coincidence with said first mentioned pivot member, and a manually movable lever for actuating said controlling means.
17. In a machine of the character de-

- scribed, in combination, a frame, a tub mounted for oscillation in said frame, means for oscillating said tub, said oscillating means including a part disposed on the side 5 of the tub and shiftable transversely to the axis of the tub, the extreme positions to which the said part may be moved controlling the operative and inoperative positions of the tub, and a manually movable lever 10 operatively connected with said shiftable part, the extreme position of the lever in one direction positioning said shiftable part whereby the tub may be oscillated, and the extreme position of the lever in the other 15 direction positioning said part whereby the tub is restored to normal position and inoperative and said oscillating means ineffective.
18. In a machine of the character described, in combination, a tub mounted for oscillatory movement, a pivot member on the tub in spaced relation to the pivotal axis of the tub, a member in slidable relation with said pivot member, a lever fulcrumed at its 20 lower end, the pivotal axis of the tub and the pivot member located in an arc struck from the fulcrum point of said lever the tub being in its normal position, means pivotally connecting said lever with said slid- 25 able member, an operating mechanism, and operating connections between said slidable member and said mechanism.
19. In a machine of the character described, in combination, a frame, a tub 30 mounted for oscillatory movement in said frame, an operating mechanism, means operatively connected with said mechanism and said tub for oscillating the latter, said operatively connected means including a part disposed on the side of the tub and shiftable transversely to the axis of the tub and arranged to be moved to two extreme positions, one constituting tub operating position and the other constituting tub inoper- 35 ative position, and a manually movable lever for moving said shiftable part and during such movement automatically restoring the tub to its normal inoperative position without stopping the movement of said operating mechanism.
20. In a machine of the character de- 40
- scribed, in combination, a tub mounted for movement and means to move said tub, including an adjustable means adapted when adjusted to one position to simultaneously 55 restore said tub to its normal position and stop its movement.
21. In a machine of the character de- 60 scribed, in combination, a tub mounted for movement and means to move said tub, including an adjustable means adapted when adjusted to one position to simultaneously restore said tub to its normal position and stop its movement, without stopping the movement of said moving means. 65
22. In a machine of the character de- 70 scribed, in combination, a tub mounted for movement and means to move said tub, including an adjustable means for varying the amplitude of oscillations of the tub adapted when adjusted to one position to 75 restore said tub to its normal position and stop its movement, independently of the amplitude of oscillations of the tub.
23. In a machine of the character de- 80 scribed, in combination, a tub mounted for movement and means to move said tub, including an adjustable means for varying the amplitude of oscillations of the tub adapted when adjusted to one position to 85 restore said tub to its normal position and stop its movement, independently of the amplitude of oscillations of the tub and without stopping the movement of said moving means.
24. In a machine of the character de- 90 scribed, in combination, a tub mounted for movement and power means to move said tub, including a controllable means movable to different positions and adapted as it is 95 moved to tub moving position to start with a light load on the power means and gradually increase the load until full load is reached, and when moved to another of its positions to restore the tub to normal stopped position.

In witness whereof we have hereunto affixed our hands this 29th day of January, 1921.

THOMAS LITWILLER.
JOHN LEADER.
